[57] CLAIM

[21] Appl. No.: 302,863

The ornamental design for a decorative glass panel, as shown and described.

DESCRIPTION

[22] Filed: Jan. 30, 1989

FIG. 1 is a front elevational view of a decorative glass panel showing our new design; and

[52] U.S. Cl. D25/103

FIG. 2 is an enlarged fragmentary cross-sectional view taken along line 2—2 of FIG. 1.

[58] Field of Search D25/48, 138, 145, 155, D25/156, 103, 104, 105; 52/171, 311, 455, 456; 248/38, 15, 210

The glass panel is transparent, and the appearance of the rear is essentially the same as the appearance of the front.

FIG. 1

FIG. 2
